UNITED STATES PATENT OFFICE.

WILLIAM L. BROBST, OF OLEONA, PENNSYLVANIA, ASSIGNOR OF TWO-THIRDS
TO MARY E. HICKS, OF SAME PLACE, AND NANCY WYKOFF, OF HAMMERS-
LEY'S FORK, PENNSYLVANIA.

DESIGN FOR AN ENVELOP.

SPECIFICATION forming part of Design No. 26,378, dated December 8, 1896.

Application filed October 28, 1896. Serial No. 610,369. Term of patent 14 years.

To all whom it may concern:

Be it known that I, WILLIAM L. BROBST, a citizen of the United States, residing at Ole-

ona, in the county of Potter and State of

5 Pennsylvania, have invented and produced
a certain new and Original Design for Envel-
ops; and I do declare the following to be a
full, clear, and exact description of the inven-
tion, such as will enable others skilled in the

10 art to which it appertains to make and use
the same.

My invention has relation to a design for
an envelop. It relates to the entire configu-
ration of the envelop.

15 My invention relates particularly to an en-
velop as illustrated in the accompanying
drawings, in which—

Figure 1 is a perspective view of an envelop
embodying my design, the same being shown
20 open to receive its contents; and Fig. 2 is a
similar view showing the envelop as it ap-
pears when sealed.

The leading features of my design appear
in the following description:

25 1 represents the flap divided into a central
section 2 and the two side sections 3 3 by the

slits 4 4. The entire outer edge 5 of the cen-
tral section 2 is serrated, while the sections
3 3 have each a serrated edge 6 and a plane
edge 7, as shown in the drawings.

30

The side flaps 8 8 have their lower converg-
ing edges 9 9 serrated, and an upper edge 10
is plane and extends inwardly to an acute
angular point 11, thence downwardly to form
a circular curve 12, from which a gummed
35 flap 13, formed with a serrated edge 14, extends
inwardly to meet a similar flap on the oppo-
site side.

Both the flaps 13 13 and the upper flap 1,
comprising the sections 2 and 3 3, are gummed
in the usual manner for sealing.

40

Having thus fully described my design,
what I claim as new, and desire to secure by
Letters Patent of the United States, is—

45 The design for an envelop, substantially as
herein shown and described.

In testimony whereof I hereunto affix my
signature in presence of two witnesses.

WILLIAM L. BROBST.
